EXTRUDED CELLULAR PANEL FOR FURNITURE

Frantz Pottiez, Brussels, Belgium, assignor to Meurop,
Société Anonyme, Rijmenam-Malines, Belgium, a cor-
poration of Belgium

Filed July 18, 1966, Ser. No. 3,103

Term of patent 14 years

(Cl. D13—1)

Fig. 1

Fig. 2

FIGURE 1 is a perspective view of an extruded cellular panel for furniture showing my design.

FIGURE 2 is an enlarged view of the portion indicated by a circle in FIG. 1.

The center is broken away and one end thereof is shown fragmentarily to indicate an article of indefinite length and width.

I claim:

The ornamental design for an extruded cellular panel for furniture, as shown and described.
